CLAIM

(51) LOC (14) Cl. **02-02**

The ornamental design for a silicone feeding bib with snap-on enclosure as shown and described.

(52) U.S. Cl. **USPC D2/861**

DESCRIPTION

(58) **Field of Classification Search**

FIG. 1 is a top, front, and right side perspective view of a silicone feeding bib with snap-on enclosure according to the present design;

USPC D2/861, 864, 862, 863, 860
CPC A41B 13/10; A41B 13/103

See application file for complete search history.

(56) **References Cited**

FIG. 2 is a front elevation view of a silicone feeding bib with snap-on enclosure according to the present design;

FIG. 3 is a rear elevation view of a silicone feeding bib with snap-on enclosure according to the present design;

FIG. 4 is a left side view of a silicone feeding bib with snap-on enclosure according to the present design;

FIG. 5 is a right side view of a silicone feeding bib with snap-on enclosure according to the present design;

FIG. 6 is a top plan view of a silicone feeding bib with snap-on enclosure according to the present design; and,

FIG. 7 is a bottom plan view of a silicone feeding bib with snap-on enclosure according to the present design.
